UNITED STATES PATENT OFFICE

ALVIN L. JOHNSON, OF WORCESTER, MASSACHUSETTS, ASSIGNOR, BY DIRECT AND MESNE ASSIGNMENTS, TO WALKER MANUFACTURING COMPANY, OF RACINE, WISCONSIN, A CORPORATION OF WISCONSIN

DOUBLE-SCREW JACK

Application filed October 19, 1926. Serial No. 142,726.

This invention relates to the type of jack which is the subject matter of my Patent No. 1,535,727 issued April 28, 1925, and it involves all the advantages of the said jack.

5 The principal other objects of the invention are to eliminate the latch construction shown in said patent and the corresponding projection on the casing provided therefor and to secure the same results without the 10 use of this feature; to provide a jack of that type with means whereby the inner screw will be brought down to its lowest level in the operation of lowering the outer screw without reference to the load on the jack, in 15 other words to make it double acting as to both screws and to provide this means in such form that it will add very little to the mechanism of the jack shown in the said patent; and to provide the jack with an anti- 20 friction bearing without interfering with the means for causing the jack to reverse at either end of its stroke, and in general to simplify the construction.

Other objects and advantages of the invention will appear hereinafter.

Reference is to be had to the accompanying drawings in which

Fig. 1 is a central vertical sectional view, with parts in section, of a jack embodying this invention, constructed in a simple form;

Fig. 2 is a horizontal sectional view of the same on the line 2—2 of Fig. 1;

Fig. 3 is a sectional view similar to Fig. 1 of the inside of the casing with the screws removed to illustrate the construction of the casing and guides;

Fig. 4 is a sectional view showing the screws in position in the bottom of the casing to illustrate the action of the cross pin when the jack is started up from its lowest position;

Fig. 5 is a similar view of the top of the jack showing the situation when the screw is starting to descend from its highest position;

Fig. 6 is a view similar to Fig. 1 showing another form of the jack;

Fig. 7 is a sectional view similar to Fig. 2 on the line 7—7 of Fig. 6;

Fig. 8 is a sectional view of the jack show-

ing screws raised to their limiting position;

Fig. 9 is a sectional view of the interior of the jack casing near the top thereof with the screws removed, taken on the line 9—9 of Fig. 7; and

Figs. 10 and 11 are horizontal sectional views on the lines 10—10 and 11—11 respectively of Fig. 8.

Referring first to the first sheet of drawings it will be seen that this jack involves most of the features of the jack shown in the above identified patent comprising the casing 10 with the passage 11 through it and the steel disc 12 closing the bottom of the jack. The cylindrical passage 11 up through the 65 casing is provided with a plurality of longitudinal guides 13 extending from near the bottom to near the top of the passage. These guides are provided, at the top and bottom respectively, with slanting ends 13^a and 13^b 70 for the same purpose as in the said patent.

Inside the passage is a left handed square threaded screw 15 having a cross pin 16 at the bottom thereof. Instead of being fixed in the screw, as shown in said patent, this 75 pin is adapted to be shifted vertically and for that reason is mounted in vertical slots 14 which allow the pin to shift up and down. This pin drops to the bottom of these passages by gravity as shown in Figs. 4 and 5 80 and is raised in them when it reaches the bottom of its stroke by engaging a central vertical spring 24 on the disc 12 as shown in Fig. 1. This brings it into contact with a surface 13^b so that it will either ratchet over 85 it or move up along two opposite guides according to the direction of rotation.

At the top of the casing is provided a circular space 17 for receiving this pin as in the other case and above the space is a ball or other anti-friction bearing 23 supported by a shoulder on the casing and supporting the nut 18 which engages with the thread of the screw 15 for operating it. This nut can be 90 operated in any desired way but I have shown an integral gear 19 on it meshing with the pinion 20 on the operating shaft 21. On the top of the casing is the cover 22 taking the thrust of the nut as in the above mentioned 95 100

patent except that this cover is simplified a little by making it a flat plate.

Inside the hollow screw 15, which is screw threaded with a left hand square thread, is the inner screw 28 provided with a work rest 29 which is fixed positively to it for supporting the load which is indicated as a part 30 of an automobile. It will be noticed that the latches shown in the above mentioned patent which project out and necessitate the provision of an engagement on the casing are eliminated.

The operation is very simple. When the outer screw reaches the bottom of its stroke, the pin 16 will rest on the spring 24 which constitutes a yielding means for holding the cross pin up. This pin ratchets over the bottoms of the guides 13, namely the surfaces 13^b, when the screw is rotated in one direction. When rotated in the direction to raise it it will engage the projecting surface of one of the guides immediately. After the screw has started, it stays in that position and the pin moves to the position shown in Fig. 3. Just as soon as it has moved upwardly a little, the spring will no longer support it, and it will be restricted by the slots 14 and will drop down to the bottom of these slots. However, it will continue to prevent the screw from turning with the nut 18. Consequently the continued rotation of the nut in that direction will raise the outer screw, carrying with it the inner screw which may be assumed to have been adjusted by hand previously upward substantially into contact with the load 30. The continued rotation of the nut will raise the outer screw to its limiting position shown in Fig. 5. Then the pin 16 will ratchet over the slanting surfaces 13^a and the outer screw will automatically and immediately commence to turn. As the inner screw is held against turning by the fixed head 29 engaging the load to be lifted, the rotation of the outer screw will then cause the inner screw to rise during the rest of the rotation of the nut 18 in the same direction. It will be noted that no change in operation is necessitated on the part of the operator and he hardly notices that any change is taking place in the operation of the jack. In fact, unless he is mechanically inclined he will never know it at all. After the load is raised to the desired position the threads of the screws hold it there so that it cannot descend of its own accord. When it is desired to lower it, the nut is rotated in the opposite direction, the effect of which is first to bring the pin 16, which is at the bottom of the slots 14, immediately into contact with the projecting edges of two opposite guides 13. The outer screw can rotate only a very small part of a revolution before it stops rotating and commences to descend by the rotation of the nut 18. The outer screw goes down without rotating and takes the inner screw with it also without rotating after

the work rest 29 comes down out of contact with the load 30. Then the load is freed from the jack and the jack can be taken out.

It will be understood that this is a practical operation in the raising of an automobile having a flat tire and the lowering of it when a new tire is put on or the old tire blown up. The car does not have to come down beyond the position from which it was started without a load. Furthermore if it did, that could be accomplished by starting the raising of the load with the outer screw raised a short distance out of the casing at the beginning of the operation.

It will be seen that this simplifies the construction of the jack shown in said patent, particularly in the manufacture of the casing 10 which can be made cylindrical from the base to the top. Any uncertainty, due to the latches shown in said patent, is also eliminated because there is a chance to use a larger spring 24 and a more durable one in position without enlarging the jack. Also by this arrangement a place is provided for the ball bearing 23 to take the weight of the whole load through the nut 18 and thus improve the operation and reduce the friction. It will be seen that this ball bearing comes at a point where the ratchet mechanism is shown in my prior patent and does not subtract anything from the travel of the outer screw.

The invention can be carried out in the form shown in the second sheet of the drawings. In this case the numerals 10, 11, 12, 13, 13^a, 13^b, 15, 16, 18, 19, 20, 21, 22, 28 and 30 are arranged exactly in the same way and refer to exactly the same parts as in the first sheet. In this case, however, the inner screw 28, which is solid in the other form is hollow throughout most of its length and provided with a square passage through its otherwise solid bottom for receiving a square rod 31. This rod enters a square hole in a plate 25 at the bottom and is headed over on the bottom and top so that it cannot come up out of it but is slidably connected with it through a square passage in it. This plate 25 has two opposite projections 26 which constitute guide pins and they enter slots 27 extending up and down the casing on opposite sides to guide this plate up and down to prevent its turning. The spring 24 is the same as in the other case but is mounted on the plate 25 and receives on its top a plate 16^a. This plate has a circular hole through it so that the rod 31 which passes through it can have relative rotation with respect to it. This plate 16^a is provided with opposite projections which constitute the cross pin 16 shown on the first sheet and this pin 16 cooperates with the guides 13 in the same way as shown on the other sheet.

Here the operation is the same except that the rod 31, which is headed over at the top, so that it will not drop down through the

screw is positively guided by the pins 26 in the guides 27 and is kept from rotation. The rest 29 can be swivelled.

It will be remembered that in the other form shown in the first sheet the screw 28 does not rotate until the screw 15 reaches the top of its travel but there is no positive means for preventing it except the load. Now in this case the guides 27 and rod 31 prevent its 10 rotation. The result is that instead of leaving the screw 28 projecting from the top of the screw 15 at practically the same height at which it started, it can be drawn down into it by the continued rotation of the shaft 21 15 until it reaches its lowermost position.

In the operation of the jack shown on sheet 2, everything is practically the same as in the other case with the exceptions noted. The nut 18 is rotated by the shaft 21 to raise the 20 outer screw from the bottom and the spring 24 causes the pins 16 to engage the guides 13 and prevent the outer screw from rotating at the beginning of the stroke and throughout the same until it reaches the top. But in this 25 case the screw 28, which cannot rotate, is positively carried up by the outer screw, having the same relative position to it all the time. When the outer screw reaches its limiting position and rotates, the pins 26 are 30 guided upward in the guides 27 thus permitting the screw 28 to rise all the way out of the screw 15.

Now in this case all the advantages obtained by the construction shown in the patent 35 and by that shown on Sheet 1 in this case are obtained and this additional advantage also, which has been explained.

Although I have illustrated and described only two forms of the invention I am aware 40 of the fact that other modifications can be made therein by any person skilled in the art without departing from the scope of the invention as expressed in the claims. Therefore I do not wish to be limited in these respects, but what I do claim is:

1. In a double screw jack, the combination with two screws, one threaded within the other, of a casing having guides along its interior, a rotatable nut engaging the threads 50 of the outer screw to operate it, means projecting from the outer screw and movable vertically with respect thereto for engaging the guides to prevent the outer screw from turning, and means for forcing said projecting means into the spaces between the guides.

2. In a double screw jack, the combination with two screws of the same hand, one threaded within the other, of a vertical casing having a series of guides along its interior, a 60 rotatable nut engaging the threads of the outer screw to operate it, relatively movable means projecting from the outer screw at the bottom for engaging the guides to prevent the outer screw from turning, and means for yieldingly forcing said projecting means

up into the spaces between the bottoms of the guides when the outer screw is in its lowermost position.

3. In a double screw jack, the combination with the two screws, one within the other, and means for rotating them, of a casing having a series of guides in the interior provided with slanting surfaces at their lower ends, said surfaces all slanting in the same direction around the casing, a pin projecting from the screw and adapted to move along the slanting end surface of any guide and then into the guide to prevent the screw from turning, said pin being movable along the screw, and yielding means under it for forcing the pin into the spaces between the guides when the screw is withdrawn into the casing.

4. In a double screw jack, the combination with the two screws, one within the other, and means for rotating them, of a casing having a plurality of vertical guides along the interior provided with slanting surfaces at both ends, a pin projecting from the screw and adapted to move along the slanting end surface of a guide and then into the guide to prevent the screw from turning, and a spring for moving the pin vertically and guiding it into one of the guides.

5. In a double screw jack, the combination with two screws, one within the other, and means for rotating the outer one, of a casing having guides extending along it inside, each provided with a slanting surface at the end, the casing also having spaces around it at the ends of said guides, a projection on the outer screw adapted to be received in said spaces and to move over one of said slanting surfaces and along the guide, and means for moving the projection vertically with respect to the outer screw to a position to guide it along one 100 of the guides and prevent rotation of the outer screw.

6. In a double screw jack, the combination with two screws one threaded in the other, and means for rotating one of them to raise or lower it, of a casing for supporting the screws, a plurality of guides for preventing the rotation of one screw when it is being raised or lowered, said guides having slanting ends to permit of their becoming effective for the purpose specified at all points around the circumference and a vertically and freely movable cross pin carried by the screw for starting the screw to move longitudinally.

7. In a double screw jack, the combination with two screws, one threaded within the other, a casing, a rotatable interiorly threaded member engaging the threads of the outer screw for raising and lowering it, the outer screw having longitudinal slots, a radial pin movable in said slots and adapted to rest at the bottoms thereof by gravity, means in the casing for engaging the ends of said pin to prevent the turning of the outer screw, said

means terminating short of the top and bottom of the casing, and means for raising the pin, when the screw reaches the bottom of the casing, so as to engage said means.

5 8. In a double screw jack, the combination with two screws, one threaded within the other, a casing, a rotatable interiorly threaded member engaging the threads of the outer screw for raising and lowering it, the outer

10 screw having longitudinal slots, a radial pin movable in said slots and adapted to rest at the bottoms thereof by gravity, means in the casing for engaging the ends of said pin to prevent the turning of the outer screw, said means terminating short of the top and bottom of the casing, and a central spring for lifting the pin when the outer screw is entirely withdrawn into the casing.

15 9. In a double screw jack, the combination with two screws, one threaded within the other, a casing, a rotatable interiorly threaded member engaging the threads of the outer screw for raising and lowering it, the outer screw having longitudinal slots, a radial pin movable in said slots and adapted to rest at the bottoms thereof by gravity, longitudinal guides in the casing, said pin being adapted to engage said guides and preventing the rotation of the outer screw, and a spring for lifting said pin into engagement with the guides.

20 10. In a double screw jack, the combination with two screws, one threaded within the other, a casing, a rotatable interiorly threaded member engaging the threads of the outer screw for raising and lowering it, the outer screw having longitudinal slots, a plate at the bottom of the outer screw having projection pins movable in said slots and adapted to rest at the bottoms thereof by gravity, means in the casing for engaging the ends of said pins to prevent the turning of the outer screw, said means terminating short of the bottom of the casing, a non-circular rod telescoping in the inner screw, a lower plate non-rotatably connected with said rod and having means engaging the casing for preventing its turning in the casing but slideable up and down therein, and means resting on the lower plate for raising the upper plate, when the outer screw reaches the bottom of the casing.

25 11. In a double screw jack, the combination with two screws, one threaded within the other, a casing, means for raising and lowering the outer screw, the inner screw having a passage through it with a non-circular hole in the bottom, a non-circular rod slidably fitting in said hole, means in the casing for preventing the non-circular rod from turning at all times, means in the casing for preventing the outer screw from turning until it reaches the end of its travel, and a spring between said means for forcing the last named means into operative position when the outer screw reaches its lowermost position.

12. In a double screw jack, the combination with two screws, one threaded within the other, of a casing having means for guiding the outer screw, a rotatable nut engaging the threads of the outer screw to raise or lower it, and a pin extending through the outer screw to engage the guiding means and shiftable vertically with respect to said outer screw. 70

13. In a lifting jack, the combination with two screws one threaded within the other, of a casing having substantially vertical guides therein with beveled upper ends, a rotatable nut supported by the casing and engaging the threads of the outer screw to operate it, and means projecting from the outer screw into engagement with the guides and vertically movable with respect to the outer screw. 75

14. In a lifting jack, the combination with two screws, one threaded within the other, of a casing having substantially vertical guides therein with beveled upper ends, a rotatable nut supported by the casing and engaging the threads of the outer screw to operate it, there being vertically elongated slots in the sides of the lower end portion of the outer screw, and a pin resting in these slots and projecting at its ends into engagement with the guides. 80

15. In a lifting jack, the combination with two screws, one threaded within the other, of a casing having substantially vertical guides therein with beveled upper ends, a rotatable nut supported by the casing and engaging the threads of the outer screw to operate it, and a pin adapted to engage the guides at its ends and loosely supported by the lower end of the outer screw so that it may move vertically with respect thereto. 90

16. In a lifting jack, the combination with two screws, one threaded within the other, of a casing having substantially vertical guides therein with beveled upper and lower ends, a rotatable nut supported by the casing and engaging the threads of the outer screw to operate it, there being vertically elongated slots in the sides of the lower end portion of the outer screw, and a pin resting in these slots and projecting at its ends into engagement with the guides, means engaging both the inner screw and the casing for preventing rotation of the inner screw without interfering with its vertical movement and a spring interposed between the pin and a portion of the last named means. 100

17. In a lifting jack, the combination with two screws, one threaded within the other, of a casing having substantially vertical guides therein with beveled upper and lower ends, a rotatable nut supported by the casing and engaging the threads of the outer screw to operate it, and a pin adapted to engage the guides at its ends and loosely supported by the lower end of the outer screw so that it may move vertically with respect thereto, means 110

engaging both the inner screw and the casing
for preventing rotation of the inner screw
without interfering with its vertical move-
ment and a spring interposed between the
5 pin and a portion of the last named means.

In testimony whereof I have hereunto af-
fixed my signature.

ALVIN L. JOHNSON.
